United States Patent Office

Des. 217,379
Patented Apr. 28, 1970

217,379

COFFEEMAKER BASE

Robert O. Ernest, Oak Park, Ill., assignor to Sunbeam Corporation, Chicago, Ill., a corporation of Illinois

Filed Mar. 26, 1969, Ser. No. 16,438

Term of patent 14 years

Int. Cl. D7—04

U.S. Cl. D44—26

Fig. 1

Fig. 2.

Fig. 6.

FIG. 1 is a perspective view of a coffeemaker base embodying my new design;
 FIG. 2 is a bottom plan view thereof;
 FIG. 3 is a top plan view thereof;
 FIG. 4 is a front elevational view thereof;
 FIG. 5 is a side elevational view thereof; and
 FIG. 6 is a fragmentary sectional view taken substantially on line 6—6 of FIG. 3.

I claim:
 The ornamental design for a coffeemaker base, as shown.
